Primary Examiner — T. Chase Nelson*Assistant Examiner* — Michelle E Wilson(74) *Attorney, Agent, or Firm* — Saidman DesignLaw Group, LLC(57) **CLAIM**

The ornamental design for a scraper, as shown and described.

DESCRIPTION

FIG. 1 is a top, front, right perspective view of a scraper showing my new design;

FIG. 2 is a bottom view thereof;

FIG. 3 is a top view thereof;

FIG. 4 is a left side view thereof, the right side view being a mirror image;

FIG. 5 is a front view thereof; and,

FIG. 6 is a rear view thereof.

The drawings include surface shading that represents contour and not surface ornamentation.

The broken lines illustrate structure or features which form no part of the claimed design.

1 Claim, 3 Drawing Sheets---
